UNITED STATES PATENT OFFICE.

ALFRED E. JUPP AND FRANK SEIGH, OF YOUNGSTOWN, OHIO.

REPEATER FOR ROLLING MILLS.

Application filed May 12, 1924. Serial No. 712,557.

The present invention relates to mechanical repeaters for rolling mills, and has for one of its objects to provide a device of this character adapted to divert a strip from one mill to a second mill out of alignment with the first mill and having provision for permitting the strip to have unrestricted movement between the mills after it has entered the second mill, whereby to enable the loop 10 to vary in length in accordance with variations in the draft of the mills.

A further object of the invention is to provide in combination with the repeater a twister associated with the receiving end of 15 the repeater for turning a strip coming from the first mill through an angle about its longitudinal axis prior to the introduction of the strip into the repeater.

A preferred embodiment of the invention 20 is illustrated in the accompanying drawings, in which,

Figure 1 is a plan view of the repeater and twisting means associated therewith, this view also illustrating diagrammatically 25 a pair of rolling mills;

Figures 2 and 3 are, respectively, trans- 30 vers sections on the lines II-II and III-III of Figure 1;

Figure 4 is an end elevation of the repeater;

Figure 5 is a side elevation of the repeater showing the same in closed position;

Figure 6 is a view similar to Figure 5 but showing the repeater in open position, and 35

Figure 7 is a fragmentary detail view.

Referring to Figure 1, 2 and 3 designate 40 a pair of rolling mills for rolling strip material, such as skelp, and 4 designates a repeater embodying my invention for diverting a strip coming from the mill 2 to the mill 3.

Interposed between the receiving end of the repeater and the horizontal mill 2 is a twister 5 for receiving a strip from the rolls 45 of the mill and turning it about its longitudinal axis through any desired angle. In the construction shown, the receiving twister is designed to turn the strip through an angle of 90 degrees so as to deliver it to the 50 repeater in a vertical position. It will be apparent, of course, that the twister may be designed to turn the strip through any other desired angle, either greater or less than 90 degrees. By reference to Figures 2 and 3, it 55 will be seen that the receiving twister is constructed of plates and channels providing a

closed passage 6 for the strip material. On either side of this passage is a chamber 7, coextensive with the twister, for water or other cooling fluid, suitable pipe connections 60 8 and 9 being provided for circulating the cooling fluid through these chambers.

Associated with the delivery end of the repeater is a delivery twister 10 for turning the strip from a vertical position into a horizontal position prior to its delivery to the horizontal mill 3. This twister may be of any usual construction.

The repeater may comprise a suitable base plate 11. Riveted or otherwise fastened to 70 this base plate is an angle 12 which constitutes one element of a guide for guiding a strip from the receiving twister 5 into the delivery twister 10. As shown, the angle 12 is bent into arcuate form. Cooperating with the angle 12 is a movable angle 13 pivotally mounted on the lower ends of rocker arms 14

and a lever 15. Rising from the base plate 11, adjacent the ends of the angle 12, is a pair of standards 16 and 17, and intermediate these standards is another standard 18. These standards are rigidly secured at their lower ends to the base plate by means of angles 19, and they are connected to each other and to the base by bracing members 75 20 and 21. Journaled in the upper ends of the standards is a horizontal rock shaft 22, upon the opposite ends of which are mounted the rocker arms 14. The lower ends of the rocker arms are pivotally connected to the angle 13 by means of removable pins 23

which extend through spaced ears 24 and 80 25 riveted to the angle. The standard 16 has a bearing portion 26 intermediate its ends in which is journaled a short horizontal rock shaft 27. This rock shaft is also journaled 85 in another vertical standard 28 spaced from the standard 16 and secured at its lower end to the base plate 11, the standard 28 being positioned outside the angle 12 and cooperat- 90 ing angle 13. On the inner end of the rock shaft 27 is mounted a rocker arm 29 which is connected by a link 30 to a rocker arm 31 carried by the rock shaft 22. On the outer end of the rock shaft 27 is mounted an op- 95 erating handle 32. Rising from the base plate 11, adjacent the inner side of the angle 12 about midway the ends thereof, is a pair 100 of spaced standards 33 secured at their lower ends to the base plate by angles 34. The lever 15 is pivoted between the standards 33 upon a pivot bolt 35 which extends through 105

110

the upper ends of said standards. Bolted to the upper end of the lever 15 is a number of weights 36. The rock shaft 22 has secured thereto, adjacent the intermediate standard 5 18, an arm 37 upon which is mounted weights 38. The angle 13 is braced by an angle 39 which extends parallel to the rock shaft 22 and has its ends secured to the angle 13 adjacent the ends of the latter. This bracing 10 angle 39 prevents the angle 13 from spreading.

When the parts are held in the closed position shown in Figure 5 by means of the operating handle 32, the angles 12 and 13 form 15 between them an arcuate guide passage 40 which registers at one end with the delivery end of the passage 6 in the receiving twister 5, and at its other end with the passage of the twister 10. In this position of the parts, 20 a strip coming from the mill 2 will pass through the receiving twister 5 and will be guided by the repeater into the delivery twister 10, from whence the strip will pass to the mill 3. After the strip has entered 25 the mill 3, the operating handle may be released, whereupon the angle 13 will be moved automatically to the open position shown in Figure 5 by the weights 36 and 38. In this open position of the angle 13, the movement 30 of the strip between the receiving and delivery twisters is unrestricted, so that after the direction of its course has been changed to divert it from one mill to the other, the strip may assume any length of loop between 35 the mills which the conditions under which it is being rolled may require. The repeater is so constructed that the strip is not subjected to pinching when the repeater is being changed from the closed to the open position. 40 The weights 36 and 38 serve to maintain the repeater normally in the open position. The receiving twister is adapted to effect a desirable cooling of the strip after it comes from the mill 2 and before it enters the repeater.

45 While we have shown and described a preferred embodiment of the invention, it will be understood that changes may be made in the construction and operation disclosed without departing from the spirit of the invention or scope of the appended claims. It 50 is also to be understood that the word "strip" as used throughout the specification and claims is used as a word of description and not of limitation.

55 We claim:

1. The combination with two sets of horizontal rolls, of a curved repeater for conducting a strip from one of said sets of rolls to the other, said repeater comprising relatively movable parts which form in the closed position thereof a horizontal curved guide passage for the strip, manually operated means for moving said parts to closed position, and means for automatically moving said parts to open position upon release

of said manually operated means and for normally maintaining them in open position to permit the strip to loop freely between said sets of rolls after it has entered the second set of rolls, substantially as described. 70

2. A repeater for rolling mills including a curved guide member, levers from which the guide member is pivotally suspended at a plurality of points, and operating means for the levers, for raising the guide and for 75 maintaining it in either raised or lowered position.

3. A repeater for rolling mills including a curved guide member, levers from which the guide member is pivotally suspended at a 80 plurality of points, operating means for the levers, and counter-weights operatively connected with the levers and arranged to counteract the weight of the guide, whereby the counter-weights tend to hold the guide 85 elevated when in one position and lowered when in another position.

4. A repeater for rolling mills including a curved guide member, a lever adjacent each end of the curved guide member from which the ends of the guide member are hung, another lever from which an intermediate portion of the guide is hung, and an operating handle by means of which the levers may be rocked to effect a substantially vertical movement of the guide. 90

5. A repeater for rolling mills including a curved guide member, levers adjacent each end of the curved guide member from which the ends thereof are hung, another lever from which an intermediate portion of the 100 guide is hung, means associated with the levers for urging them toward a horizontal position whereby said levers tend to hold the guide in an elevated position, and an operating handle for moving the guide to a lowered position. 105

6. A repeater for rolling mills including a curved guide member, a lever adjacent each end of the curved guide member from which the ends thereof are hung, another lever from which an intermediate portion of the guide is hung, and means for operating the first named levers, said means including a rock shaft to which the levers are connected, and an operating extension on the rock shaft. 110

7. A repeater for rolling mills including a curved guide member, levers from which the guide member is pivotally suspended at a plurality of points, and a second fixed curved guide member cooperating with the first. 120

8. A repeater for rolling mills including a fixed curve guide, a movable curved guide member, a plurality of levers from which the curved guide member is pivotally suspended at a plurality of points, said first guide member being in the form of an angle having the legs thereof turned downwardly and inwardly, while the fixed guide member has a 125 130

vertical leg spaced inwardly from the vertical leg of the movable guide member.

9. A repeater for rolling mills including outer and inner guide members, said outer guide member comprising a curved bar in the form of an angle having a horizontal leg which is turned inwardly and a vertical leg which is turned downwardly at the outer edge of the horizontal leg, said lower guide member being substantially concentric with the upper guide member and being spaced inwardly with respect to the vertical flange thereof, and means for raising and lowering the outer guide member with respect to the inner guide member.

10. A repeater for rolling mills including upper and lower guide members, said upper guide member comprising a curved bar in

the form of an angle having a horizontal leg which is turned inwardly and a vertical leg which is turned downwardly at the outer edge of the horizontal leg, said lower guide member being substantially concentric with the upper guide member and being spaced inwardly with respect to the vertical flange thereof, means for raising and lowering the upper guide member with respect to the lower one, said means including a plurality of levers from which the upper guide member is suspended at a plurality of points, and means for rocking the levers.

In testimony whereof we have hereunto set out hands.

ALFRED E. JUPP.
FRANK SEIGH.
